CLAIM

The ornamental design for a laptop computer, as shown and described.

DESCRIPTION

FIG. 1 is a front perspective view of a laptop computer, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is an enlarged view of the portion 8 in FIG. 1; and, FIG. 9 is an enlarged view of the portion 9 in FIG. 1.

The even-dash broken lines, illustrating portions of the laptop computer form, no part of the claimed design. The dot-dot-dash broken lines, encircling enlargement portions of the claimed design, are for annotation purposes only and form no part of the claimed design.

1 Claim, 9 Drawing Sheets
